CLAIM

The ornamental design for a display panel, as shown and described.

DESCRIPTION

FIG. 1 is a perspective view of the display panel;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof; and,
FIG. 8 is an enlarged view of a region “8” in FIG. 1.
The broken lines and the unshaded areas shown in the drawings represent portions of the display panel that form no part of the claimed design.

1 Claim, 8 Drawing Sheets
